US00D567624S

(12) **United States Design Patent** (10) Patent No.: **US D567,624 S**
Ricereto (45) Date of Patent: **** Apr. 29, 2008**

(54) **KNOB**

(75) Inventor: **Michael Hart Ricereto**, Baltimore, MD (US)

(73) Assignee: **Newell Operating Company**, Atlanta, GA (US)

(**) Term: **14 Years**

(21) Appl. No.: **29/278,562**

(22) Filed: **Apr. 2, 2007**

(51) LOC (8) Cl. **08-06**

(52) U.S. Cl. **D8/307; D8/310**

(58) Field of Classification Search .... **D8/300, D8/307, 310, DIG. 2, 350, 352; D23/250-254; 292/336.3, 337, 347, 357, 356; 16/402, 412, 16/441, DIG. 30, 110.1**

See application file for complete search history.

(57) **CLAIM**

I claim the ornamental design for a knob, as shown and described.

DESCRIPTION

FIG. 1 is a perspective view of a knob of the claimed invention;

FIG. 2 is a side view of the knob shown in FIG. 1, each side view being identical thereto;

FIG. 3 is a front view of the knob shown in FIG. 1; and, FIG. 4 is a rear view of the knob shown in FIG. 1.

Features shown in broken lines in the drawings form no part of the claimed design.
